UNITED STATES PATENT OFFICE.

LEON LANZKRONER, OF NEW YORK, N. Y.

REFRIGERATOR.

Application filed August 9, 1921. Serial No. 490,910.

To all whom it may concern:

Be it known that I, LEON LANZKRONER, a citizen of Austria, and a resident of the city of New York, borough of Manhattan, in the 5 county and State of New York, have invented a new and Improved Refrigerator, of which the following is a full, clear, and exact description.

This invention relates to refrigerators, 10 and has for an object the provision of means whereby the drippings from a refrigerator can be very simply and efficiently collected and removed and whereby the spilling of the drippings on the floor is avoided.

15 Another object resides in the provision of means whereby plenty of cracked ice and icewater can be had at all times, this arrangement being formed in the structure of the refrigerator itself.

20 A further object resides in the provision of means whereby a maximum of storage space is provided and whereby an exceptionally large ice capacity is provided when desired.

25 A still further object resides in the provision of means whereby the entire structure of the ice box can be very readily cleaned to keep the contents in an entirely sanitary condition at all times.

30 Another object resides in the provision of means whereby all the moisture and water formed within the box is collected in one receptacle.

35 A further object resides in the provision of means whereby in removing the drippings from the ice box the splashing thereof from the receptacle in which they are contained is eliminated.

40 A still further object resides in the particular construction and arrangement of parts which are hereinafter described and claimed and shown in the accompanying drawings.

The invention is illustrated in the drawings, of which—

45 Figure 1 is a front elevation of the box; Figure 2 is a vertical transverse section taken on the line 2—2 of Figure 1;

Figure 3 is a horizontal section taken on the line 3—3 of Figure 1;

50 Figure 4 is a horizontal section taken on the line 4—4 of Figure 1;

Figure 5 is a horizontal section taken on the line 5—5 of Figure 1; and

55 Figure 6 is a vertical longitudinal section taken on the line 6—6 of Figure 2.

As shown in the drawings, the preferred

form of my invention comprises an ice box formed with a body portion 1 having inner and outer walls 2 and 3 separated by any suitable insulating material 4, such as cork. 60 The front of the ice box is provided with doors 5 and 6 leading to the ice chamber, with doors 7 and 8 leading to storage chambers, and with a drawer or cabinet 9 adapted to receive the drippings as well as to 65 receive articles to be stored. Within the ice box is a metallic lining, such as 10, lining the wall throughout. This lining may, preferably, be of white enamel or some other suitable metal easily kept clean and sanitary. 70 In the upper portion of the box I provide brackets, such as 11, on which a flat shelf is adapted to rest. This shelf is formed of two sections 12 and 13 pivoted at their abutting edges. This shelf or plate is disposed 75 to form a chamber thereabove which may receive articles to be stored; and below this shelf, preferably, ice is placed. In inserting the ice within the box, the front portion 13 of the shelf can be raised to permit of a 80 ready insertion of the ice. Furthermore, if desired, the front section 13 may be raised and laid flat against the section 12, and then both sections may be raised flat against the back of the box if it is desired to fill this 85 entire space with ice. The ice chamber and the upper storage chamber are disposed substantially opposite the doors 5 and 6.

Slightly below the level of the doors 5 and 6 there is disposed a partition, such as 90 14, which extends completely across the box. This partition is provided, as shown at Fig. 6, with transversely extending flange portions 15 and 16 between which the cake of ice is adapted to be disposed. On the outside of each partition a storage place is 95 formed. In the central portion of the partition, between the flange plates 15 and 16, a chamber 17 is formed. This chamber extends downwardly a considerable distance 100 and is of a width extending approximately two-thirds across the depth of the ice box from the rear to the front. This chamber 17 is adapted to receive cracked ice. The bottom of this chamber is provided with a 105 faucet or outlet 18 which when open permits the water formed in this chamber to pass out. The water formed in this chamber is not only from the cracked ice but from the cake of ice resting on the shelf 14. In 110 front of the chamber 17 containing the cracked ice is disposed a removable recep-

tacle 18' fitting in the space left between the chamber 17 and the front wall of the ice box. This receptacle is adapted to contain water, which becomes very cold by reason of the 5 contact of one of its walls with the cracked ice chamber 17 as well as because of its proximity to the cake of ice on the shelf 14. This receptacle is also provided with a faucet 19 extending through the front wall of the 10 ice box between the doors 7 and 8. The receptacle 18' and the chamber 17 are not very wide, so that they lie back of the partition between doors 7 and 8 and permit storage space, such as 20 and 21, and 22 and 23, to 15 be formed on each side thereof. Between the spaces 20 and 21 and 22 and 23 shelves 24 and 25 are provided. Toward the bottom of the ice box a shelf or partition 26 is provided. On this partition 26 a perforated 20 tray 27 rests. The central portion of the partition 26 is provided with apertures, such as 28, through which any moisture or water formed on the outside of the cracked-ice receptacle and the ice-water receptacle may 25 pass into a drip pan 29 disposed on the bottom of the refrigerator. The faucet 18 extends through the partition 26 in the tray 27 into close proximity to the drip pan 29. This drip pan 29 is disposed within a portion of 30 a drawer 30 which is provided with storage receptacles 31 and 32 on either side of the space containing the drip pan 29. This drawer may be pulled out at will to empty the drippings. From the upper rear edge of 35 the drip pan 29 a baffle plate 33 extends forwardly and downwardly slightly to prevent the water or drippings from splashing out of the pan 29 when the drawer is pulled out of the refrigerator. The drip pan is provided with handles, such as 34, whereby it 40 may be removed from its nest within the drawer 30 and the water emptied therefrom.

It will, therefore, be observed that I provide a refrigerator in which a maximum 45 amount of storage space is provided; in

which ice water and cracked ice are available at all times and in ample quantity; in which an increased amount of ice may be stored in the refrigerator, as desired; in which all the moisture or water formed within the refrigerator is efficiently collected in a single pan the size of which is sufficient to receive all the water that possibly could form from the maximum amount of ice placed within the refrigerator; and in which, in removing the drippings from the refrigerator, they do not get on the floor and can be very readily removed.

What I claim is:

1. A refrigerator, a drip pan disposed therebeneath, and a partition extending entirely across the bottom of the refrigerator above the drip pan, a perforated tray supported above said partition, said partition having a plurality of perforations therein 65 over the drip pan and adapted to collect any moisture falling thereon and permit it to drain into the drip pan.

2. A refrigerator comprising a casing including upper and lower chambers and a sectional folding partition removably mounted in the upper chamber between the lower chambers and the top of the casing, whereby an upper provision chamber may be provided above the ice chamber, or the ice capacity of the refrigerator be increased.

3. A refrigerator comprising an ice chamber, a storage chamber, above the same, said chambers extending the entire width and depth of the refrigerator, and a sectional shelf disposed and supported between said chambers and forming a partition wall therebetween, said sections hingedly connected, and adapted to be folded on each other and against a wall of the upper storage chamber whereby the storage chamber and ice chamber may be combined as one to increase the ice capacity of the refrigerator.

LEON LANZKRONER.
